(57) **CLAIM**

The ornamental design for a battery swapping station, as shown and described.

DESCRIPTION

FIG. 1 is a front perspective view of a first design of a battery swapping station;

FIG. 2 is another front perspective view of the first design of the battery swapping station;

FIG. 3 is a rear perspective view of the first design of the battery swapping station;

FIG. 4 is another rear perspective view of the first design of the battery swapping station;

FIG. 5 is a front view of the first design of the battery swapping station;

FIG. 6 is a rear view of the first design of the battery swapping station;

FIG. 7 is a left view of the first design of the battery swapping station;

FIG. 8 is a right view of the first design of the battery swapping station;

FIG. 9 is a top view of the first design of the battery swapping station;

FIG. 10 is a front perspective view of a second design of the battery swapping station;

FIG. 11 is another front perspective view of the second design of the battery swapping station;

(Continued)

FIG. 12 is a rear perspective view of the second design of the battery swapping station;
 FIG. 13 is another rear perspective view of the second design of the battery swapping station;
 FIG. 14 is a front view of the second design of the battery swapping station;
 FIG. 15 is a rear view of the second design of the battery swapping station;
 FIG. 16 is a left view of the second design of the battery swapping station;
 FIG. 17 is a right view of the second design of the battery swapping station; and,
 FIG. 18 is a top view of the second design of the battery swapping station.

The bottom of the first design of the battery swapping station is flat and unornamented. The bottom of the second design of the battery swapping station is flat and unornamented.
